A. BLOCH.
LAMP SHADE HOLDER.
APPLICATION FILED JAN. 14, 1918.

Patented May 7, 1918.

FIG. 1.

FIG. 2.

FIG. 3.

FIG. 4.

FIG. 5.

Inventor
Aaron Bloch
By his Attorneys
Edgar Gates & Co.

UNITED STATES PATENT OFFICE.

AARON BLOCH, OF BROOKLYN, NEW YORK.

LAMP-SHADE HOLDER.

1,265,167.

Specification of Letters Patent.

Patented May 7, 1918.

Application filed January 14, 1918. Serial No. 211,760.

To all whom it may concern:

Be it known that I, AARON BLOCH, a citizen of the United States, and residing at Brooklyn, in the county of Kings and State 5 of New York, have invented certain new and useful Improvements in Lamp-Shade Holders, of which the following is a specification, such as will enable those skilled in the art to which it appertains to make and

10 use the same.

This invention relates to shade holders for lamps, and the object thereof is to provide an improved device of this class which may be applied to lamps or illuminating burners 15 of various kinds and classes, including oil burners, gas burners and electric light bulbs; a further object being to provide a device of the class specified which is simple in construction, efficient in use and comparatively 20 inexpensive.

The invention is fully disclosed in the following specification, of which the accompanying drawing forms a part, in which the 25 separate parts of my improvement are designated by suitable reference characters in each of the views, and in which:—

Figure 1 is a sectional side view showing my improved shade holder applied to an ordinary gas lamp;

30 Fig. 2 a section on the line 2—2 of Fig. 1;

Fig. 3 a sectional detail view of one part of my improved holder;

Fig. 4 a side view of a modified form of my 35 improved shade holder designed for use in connection with an electric bulb lamp; and,

Fig. 5 a section on the line 5—5 of Fig. 4.

In the practice of my invention, as shown in Figs. 1 to 3 inclusive, I provide a shade holder comprising three upright arm members a which are L-shaped in form and the shorter arms a^2 of which are provided with flat shanks a^3 having arc-shaped portions a^4 provided at their ends with radial jaws a^5 , and the parts a^3 and a^4 are provided with 45 apertures a^6 and a^7 .

In forming the complete holder, three of the parts a are placed together as shown in Figs. 1 and 2, and rivet pins or similar devices b are passed through the apertures 50 a^6 and a^7 of the separate parts and headed as shown in Fig. 2, and this forms a ring-shaped central base member c which may be passed down over a burner tip or gas nozzle, or the base of a burner of any kind 55 or class, as indicated in Fig. 1.

On the tops of arms a , or secured to the tops of said arms in an annular cap, or shade holder d which is step-shaped in the construction shown, or provided with an annular base d^2 above which is a reduced annular neck portion d^3 and an ordinary shade 60 may be suspended from this device in the usual manner, or a shade of any desired construction, and when desired a vessel containing water may be placed on said cap or 65 holder. In the construction shown the arms a are riveted to the base of the cap or shade holder d as shown at d^4 , but this connection may be made in any desired manner.

The arms or parts a are composed of, or 70 formed from, a light rod or heavy wire and in Figs. 4 and 5, I have shown a modification which is particularly designed for use in connection with electric bulb lamps, and which is the same in all respects as the construction shown in Figs. 1 to 3 inclusive, except that only two of the arms a are employed, and the upper end portions of these arms are made longer and curved as shown at a^8 , and the tops of these arms may be 75 connected in any desired manner, my invention relating only to the base construction shown by which connection is made with the burner or burners.

Having fully described my invention, 80 what I claim as new and desire to secure by Letters Patent, is:—

1. A lamp shade holder composed of a plurality of L-shaped arms, the shorter portions of which are provided with flattened 90 shanks having arc-shaped extensions provided at their ends with flat radial jaws, said shanks and jaws being riveted together, substantially as shown and described.

2. A lamp shade holder composed of separate parts provided at one end with flattened shanks having arc-shaped extensions provided at their ends with flat radial jaws, said shanks and jaws being secured together to form a circular head.

In testimony that I claim the foregoing as my invention I have signed my name in presence of the subscribing witnesses this 8th day of January, 1918.

AARON BLOCH.
